Robert Davol Budlong, Skokie, Ill., and Jack De Young, Grand Haven, Mich., assignors to Zenith Radio Corporation, a corporation of Illinois

Application April 27, 1949, Serial No. 2,293

Term of patent 3½ years

(Cl. D56—4)

To all whom it may concern:

Be it known that we, Robert Davol Budlong, a citizen of the United States, residing at Skokie, in the county of Cook, State of Illinois, and Jack De Young, a citizen of the United States, residing at Grand Haven, Michigan, have invented a new, original, and ornamental Design for a Radio Television Cabinet, of which the following is a specification, reference being made to the accompanying drawings, forming a part thereof, in which:

Figure 1 is a perspective view of a radio television cabinet, showing our new design,

Figure 2 is a front view of the radio television cabinet with the image reproducer exposed, and

Figure 3 is a front view of the radio television cabinet with the phonograph and radio compartments opened.

The rear of the cabinet is unornamented.

We claim:

The ornamental design for a radio television cabinet, as shown and described.

ROBERT DAVOL BUDLONG.
JACK DE YOUNG.
